E. J. MILLER.
FOOTREST FOR SEWING MACHINES.
APPLICATION FILED APR. 16, 1920.

1,368,957.

Patented Feb. 15, 1921.

Inventor
E.J. Miller

By *Asa Wright* Attorney

UNITED STATES PATENT OFFICE.

ELLEN J. MILLER, OF COLORADO SPRINGS, COLORADO.

FOOTREST FOR SEWING-MACHINES.

1,368,957.

Specification of Letters Patent. Patented Feb. 15, 1921.

Application filed April 16, 1920. Serial No. 374,289.

To all whom it may concern:

Be it known that I, ELLEN J. MILLER, a citizen of the United States, residing at Colorado Springs, in the county of El Paso 5 and State of Colorado, have invented certain new and useful Improvements in Footrests for Sewing-Machines, of which the following is a specification, reference being had therein to the accompanying drawing.

10 This invention relates to certain new and useful improvements in foot rests for sewing machines, the object being to provide a foot rest which can be readily attached to any part of the frame of the sewing machine to 15 enable the operator to rest her foot in handling the goods being operated on.

Another object of my invention is to provide a foot rest which is slidably mounted in a support secured to the frame so that the 20 same can be moved out of the way when not in use.

Another and further object of the invention is to provide a foot rest which is exceedingly simple and cheap in construction 25 and one which is composed of a support having means for clamping the same to the frame of the sewing machine to provide it with a guide way to receive the slidably mounted foot rest.

30 Other and further objects and advantages of the invention will be hereinafter set forth and the novel features thereof defined by the appended claims.

In the drawings,

35 Figure 1 is a perspective view of a portion of the sewing machine showing the application of my improved construction of foot rest.

40 Fig. 2 is a perspective view of the foot rest detached.

In the drawing 1 indicates the frame of the sewing machine which may be of any of the well known constructions now in use and 2 my improved construction of foot rest 45 showing the same attached to the frame.

The foot rest comprises a support 3 provided with a fixed jaw 4 and a movable jaw 5 adapted to be clamped over the frame of the sewing machine by a bolt 6 and wing 50 nut 7 and by this construction the support 3 may be easily and quickly attached to any part of the sewing machine frame but of course I am aware that the detailed construction of clamping means is not essential 55 as other clamping means can be employed without departing from the spirit of my invention.

The support is provided with a reduced extension 8 provided with an opening 9 forming a guide way adapted to receive a 60 rod 10 which is provided with a fixed knob 11 at one end and a threaded portion 12 at its opposite end over which is arranged a threaded knob 13. By constructing the foot rest proper of a rod in this manner the same 65 can be readily inserted in the guide way or removed therefrom. When the foot rest is to be used it is forced inwardly under the body of the sewing machine in position to receive the foot of the operator and when not 70 in use it is moved outwardly so as to be out of the way of the operator when sewing on the machine.

From the foregoing description it will be seen that I have provided a foot rest for a 75 sewing machine comprising a support having means for attaching the same to the frame of the sewing machine and provided with a guide way in which is slidably mounted a rod forming a foot rest having a knob 80 at each end to prevent the foot rest from slipping off and to facilitate the insertion and removal of the rod from the support.

What I claim is:—

1. A foot rest for sewing machines comprising a support having means for attaching the same to the frame of a machine, a foot rest slidably mounted in said support and capable of being extended to either side thereof. 90

2. A foot rest for sewing machines comprising a support having means for clamping the same to the frame of a machine, said support being provided with a guide way, a rod slidably mounted in said guide way having a knob at each end, said rod being capable of being moved outwardly in either direction to form a support. 95

3. A foot rest for sewing machines comprising a support having a reduced extension provided with an opening, a rod slidably mounted in said opening, said rod having a fixed knob at one end and a removable knob at its opposite end, said rod being capable of being moved within said support 100 to form a foot rest to either side thereof. 105

In testimony whereof I hereunto affix my signature in the presence of two witnesses.

ELLEN J. MILLER.

Witnesses:

SAMUEL R. MAXWELL,
H. S. WILLIAMSON.
